(57) **CLAIM**

The ornamental design for a convertible toddler bed with a curved headboard, as shown and described.

DESCRIPTION

FIG. 1 is an overall perspective view of a first alternate appearance of a convertible toddler bed with a curved headboard showing my new design;

FIG. 2 is a left side elevation view thereof, with the right side elevation view being a mirror image thereof;

FIG. 3 is a top plan view thereof;

FIG. 4 is a front elevation view thereof;

FIG. 5 is a rear elevation view thereof;

FIG. 6 is an overall perspective view of a second alternate appearance of the convertible toddler bed with a curved headboard of FIG. 1;

FIG. 7 is a left side elevation view of the second alternate appearance of the convertible toddler bed with a curved headboard of FIG. 6, with the right side elevation view being a mirror image thereof;

FIG. 8 is a front elevation view of the second alternate appearance of the convertible toddler bed with a curved headboard of FIG. 6, with the rear elevation view being identical to FIG. 5; and,

FIG. 9 is a top plan view of the second alternate appearance of the convertible toddler bed with a curved headboard of FIG. 6.
